BRAKE SHOE

Original Filed Aug. 4, 1926

FIG. 3

VINCENT BENDIX
INVENTOR
BY

Dr. W. McConkey
ATTORNEY

UNITED STATES PATENT OFFICE

VINCENT BENDIX, OF SOUTH BEND, INDIANA, ASSIGNOR TO BENDIX BRAKE COMPANY, OF SOUTH BEND, INDIANA, A CORPORATION OF ILLINOIS

BRAKE SHOE

Application filed August 4, 1926, Serial No. 126,959. Renewed May 20, 1931.

This invention relates to brakes, and is illustrated as embodied in an internal expanding automobile brake. An important object of the invention is to construct the shoe 5 in a novel manner, to enhance its lightness and strength, and at the same time to lessen the cost of manufacture. The novel shoe also has a very pleasing appearance.

I prefer to construct the shoe by attaching 10 to an outer arcuate part, which may carry the lining or which may itself be a section of metal brake lining, a stiffening member having integral tongues forming the attaching means. In order to form inclined braces, the 15 tongues may diverge at acute angles from the plane of the stiffening member, preferably alternating on opposite sides thereof. It is very desirable to bend the end of each tongue toward the side edge of the shoe, forming it on 20 an arc lengthwise of the shoe, so that it fits closely against the inner face of the outer part.

An important feature of novelty relates to 25 securing the outer part and the stiffening member, and preferably also the lining, together by a single series of fastenings, so that the assembly of the shoe and the attaching of the lining may take place simultaneously, thus simplifying the assembly and lessening 30 the cost of manufacture.

Other desirable features relate to a bracing member for the end of the arcuate outer part, which member in one embodiment is integral 35 with a novel cam thrust plate, and to a separate member bracing the other end of the shoe and cooperating with one end of the stiffening member to form a pair of spaced pivot arms, and to the particular arrangement 40 of the above-described bracing tongues, especially in their relation to openings through the stiffening member. These and other novel combinations of parts and desirable particular details of construction will be apparent from the following description 45 of the illustrative embodiment shown in the accompanying drawings, in which:

Figure 1 is a vertical section through the 50 brake, just inside the head of the brake drum, showing the novel shoes in side elevation;

Figure 2 is an inside development of one

end shoe; i. e. it is an inside view of one end shoe as it would look if straightened out;

Figure 3 is a similar inside development of the center shoe;

Figure 4 is a section on the line 4—4 of Figure 2, showing the novel thrust member at the end of the shoe;

Figure 5 is a section through one of the shoes, for example on the line 5—5 of Figure 2; and

Figure 6 is a view corresponding to Figure 5, but showing a shoe with metal lining.

The brake shown in Figure 1 includes a rotatable drum 10, at the open side of which is a support such as a backing plate 12, and within which are arranged three shoes 14, 16, and 18. Shoes 14 and 18 are preferably interchangeable. Shoes 14 and 18 have spaced arms at their ends straddling opposite ends of shoe 16, and connected thereto by pivots 70 or the like 20 and 22. Shoe 16 is anchored on a pivot 24 carried by the backing plate, and passing through relatively large openings 26 in the arms at the end of shoe 14. The brake is applied by means such as a double cam 28, 75 against the resistance of a return spring 30, and shoe 16 is applied by shoes 14 and 18 (principally the latter) against the resistance of an auxiliary return spring 34.

The present invention relates to the construction of shoes 14, 16, and 18, to make them lighter, stronger, and cheaper, and at the same time to enhance their appearance. Part of the subject-matter of the present application is disclosed in my prior co-pending application No. 110,632, filed May 21, 1926, such subject-matter being continued herein from said prior application.

Each of the shoes includes an outer arcuate or cylindrically-curved band or supporting member 36, carrying the brake lining 38, or in lieu thereof an arcuate piece of metal brake lining 40 (Figure 6) of bronze or other metal having an adequate coefficient of friction. On the inner side of the band 36 or 40 is arranged a stiffening member 42, slotted inwardly from its outer edge to form tongues 44 which are bent at acute angles to the plane of the stiffening member to form inclined braces engaging the inner face of part 36. The outer

ends of tongues 44 are bent to extend toward the side edges of part 36, and are curved cylindrically lengthwise of the shoe, to fit closely against the inner face of part 36 (or 40).

5 Alternate tongues 44 are inclined in opposite directions from the plane of the stiffening member 42, so that both sides of band 36 are adequately supported.

According to an important feature of the 10 invention, a single set of rivets or other fastenings 46 forms the sole means securing lining 38 to band 36, and band 36 to the stiffening member 42. In making the shoe, the lining and band and stiffening member are clamped 15 in a suitable fixture, while the fastenings are inserted. This eliminates the step of securing band 36 and member 42 together before attaching the lining. However, if preferred, one or two tongues 44 may be spot-welded to 20 band 36 as a preliminary fastening, leaving the lining fastenings 46 to constitute the means for permanently securing these two parts together.

At the cam end of each of the shoes 14 and 25 18 is arranged a novel thrust member 48 doubled on itself to form parts 50 engaging and secured to opposite sides of member 42 at its end. I prefer to extend one of the parts 50, as shown in Figure 4, to form a tongue 52 30 similar to the tongues 44, and supporting the end of band 36 at the side opposite the last tongue 44.

Where the openings 26 come in member 42, a radially straight or plane portion 54 is left, 35 and is arranged to engage part of the band 36 along its outer edge to support it at its center.

In order to form the spaced arms at the lower ends of shoes 14 and 18, the stiffening member 42 may be deflected to one side of 40 the center of the shoe just above opening 26 (see Figure 2), and projected beyond the end of part 36 as a pivot arm 56. The last tongue 44 on this part of member 42 supports the end of part 36 at one side. A separate part 58 is secured to member 42 at the 45 point where it is deflected, and is offset therefrom and projected beyond the end of the shoe to form the other pivot arm 60. This part 58 is shown formed with tongues 62 on opposite sides of opening 26, and similar to 50 tongues 44, and the second of which supports the end of band 36 at the side opposite the last tongue 44. Arms 56 and 60 may have integrally-drawn bearings 64 to embrace the 55 pivot 20 or 22.

Shoe 16 has no cam plate at its end, and to support the side of band 36 at its ends opposite the end tongues 44 it is provided with inclined strips or braces 66 similar to the 60 tongues except that they are separate pieces. Member 42 of shoe 16 is provided with three bushings 68 for pivots 20 and 22 and anchor 24.

65 While an illustrative construction has been described in detail, it is not my intention to

limit the scope of the invention to that particular construction, or otherwise than by the terms of the appended claims.

I claim:

1. A brake shoe having, in combination, a 70 cylindrically-curved outer band, a stiffening device on the inner side of said band, friction lining on the outer face of the band, and fastenings passing directly through the lining and the band and through a part of said 75 stiffening device and forming the sole means of securing the lining to the band and the sole means of securing the band to the stiffening device.

2. A brake shoe having, in combination, a 80 cylindrically-curved outer band, a stiffening device on the inner side of said band, friction lining on the outer face of the band, and fastenings passing directly through the lining and the band and through a part of said 85 stiffening device and forming the sole means of securing the lining to the band.

3. A brake shoe comprising three principal parts, viz.: (1) an arcuate band, (2) friction lining on the face of the band, and (3) 90 a stiffening device engaging the band opposite the lining, together with a series of fastenings, all of which pass through the lining and the band and the stiffening device and which hold said three principal parts together. 95

4. A brake shoe comprising, in combination, an arcuate outer part, a separate stiffening member having tongues extending toward the opposite side edges of said outer part 100 and secured thereto, and a brace member opposite the tongue at the end of the shoe and connecting the stiffening member and the outer part.

5. A brake shoe comprising, in combination, an arcuate outer part, a separate stiffening member having tongues extending toward the opposite side edges of said outer part 105 and secured thereto, and a brace member opposite the tongue at the end of the shoe and connecting the stiffening member and the outer part, said brace member having a part at the end of the shoe arranged to serve as a thrust part to be engaged by a brake-applying device. 110

6. A brake shoe comprising, in combination, an arcuate outer part, a separate stiffening member having tongues extending toward the opposite side edges of said outer part 115 and secured thereto, and a brace member opposite the tongue at the end of the shoe and connecting the stiffening member and the outer part, said brace member having an integral portion extending across the end of the shoe and arranged to serve as a thrust part to be engaged by a brake-applying device. 120

7. A brake shoe having an arcuate outer part and a stiffening web, in combination with a thrust member at the end of the shoe 125 130

- having parts engaging and secured to opposite sides of the end of said web, and at least one of which parts is extended into engagement with the outer part to serve as a brace therefor.
5. A brake shoe having an arcuate outer part and a stiffening member having tongues secured to the inner face of said part and extending beyond the end thereof, together with a separate part projecting beyond said end generally parallel to the projecting portion of the stiffening member, said separate part and said projecting portion forming spaced pivot arms for the shoe.
10. A brake shoe having an arcuate outer part and a stiffening member having tongues secured to the inner face of said part and extending beyond the end thereof, together with a separate part projecting beyond said end, said separate part and the projecting portion forming pivot means for the shoe, and said separate part and said stiffening member having tongues respectively supporting the opposite sides of the outer part at its said end.
15. 10. A brake shoe having, in combination, an arcuate outer part, a stiffening member approximately in the central plane of said part and deflected to one side of said plane near the end of the shoe and having a tongue supporting the side of the outer part at said end and a separate part extending toward said end of the shoe from the point where the stiffening member is deflected and having a tongue supporting the other side of the outer part at said end.
20. 11. A brake shoe comprising, in combination, an arcuate outer part, and a stiffening member secured thereto and including a portion engaging with its outer edge the inner surface of said outer part and formed with a transverse opening, said member having tongues on opposite sides of said opening, each of which is secured to the inner face of the outer part near its side edge.
25. 12. A brake shoe comprising, in combination, an arcuate outer part, and a stiffening member secured thereto and including a portion engaging with its outer edge the inner surface of said outer part and formed with a transverse opening, said member having tongues on opposite sides of said opening, each of which is secured to the inner face of the outer part near its side edge, said tongues being inclined to the plane of
30. 13. A brake shoe including separate web and band members secured together and forming a structure generally T-shaped in cross section, in combination with a reinforcing angle-shaped member having one portion secured to the side of the web member and another portion secured to the inner face of the band member.
35. 14. A brake shoe comprising a band, a stiffening member upon one side of the band, a friction lining upon the opposite side of the band and fastening devices common to said three members.
15. A brake shoe comprising a band, a stiffening member extending therealong upon one side, a friction lining upon the opposite side of the band, and fastening means extending through the three members securing them together.
20. 16. A brake shoe comprising, in combination an arcuate outer part, and a stiffening device having integral tongues diverging from its plane at acute angles to engage said outer part.
25. 17. A brake shoe comprising, in combination, an arcuate outer part, and a stiffening device having integral tongues alternately bent in opposite directions and diverging from the plane of said device at acute angles to engage said outer part.
30. 18. A brake shoe comprising an arcuate band portion supported upon a radial stiffening portion having inclined integral tongues projecting from opposite sides and engaged with the band portion.
35. 19. A brake shoe comprising an outer arcuate band supported upon a radially extending stiffening web provided with inclined tongues projecting generally laterally therefrom into engagement with the band beyond the plane of the web.
- In testimony whereof, I have hereunto signed my name.
